Patented Apr. 19, 1960

187,704

PLAYGROUND LADDER AND SLIDE

Douglas A. Deeds, San Diego, Calif.

Application October 8, 1959, Serial No. 57,861

Term of patent 14 years

(Cl. D34—5)

FIG. 1

FIG. 2

FIG. 3

FIG. 4

Figure 1 is a perspective view of the left side of the ladder and slide;

Figure 2 is a top plan view of the ladder and slide;

Figure 3 is a front view looking to the right of Figure 1; and

Figure 4 is a rear view looking to the left of Figure 1.

I claim:

The ornamental design for a playground ladder and slide, as shown.
